CLAIM

The ornamental design for an adhesive patch system, as shown and described.

DESCRIPTION

FIG. 1 is a front perspective view of an adhesive patch system showing our new design.

FIG. 2 is a front view of the adhesive patch system of our new design.

FIG. 3 is a back view of the adhesive patch system of our new design.

FIG. 4 is a left side view of the adhesive patch system of our new design.

FIG. 5 is a right side view of the adhesive patch system of our new design.

FIG. 6 is a front perspective view of the adhesive patch system of our new design with a single adhesive patch removed from the system; and,

FIG. 7 is a front perspective view of the adhesive patch system of our new design with a single adhesive patch removed from the system with one half of the liner of the single adhesive patch removed.

FIG. 1

FIG. 2

FIG. 3

FIG. 4

FIG. 5

FIG. 6

FIG. 7
